(57) **CLAIM**

The ornamental design for a mount for electronic device, as shown and described.

DESCRIPTION

FIG. 1 is a front, first side, and top perspective view of a mount for electronic device embodying the new design; FIG. 2 is a back, second side, and bottom perspective view thereof;

FIG. 3 is a front view thereof;

FIG. 4 is a back view thereof;

FIG. 5 is a second side view thereof;

FIG. 6 is a first side view thereof;

FIG. 7 is a top view thereof; and,

FIG. 8 is a bottom view thereof.

The uniform repeating broken lines depict portions of a mount for electronic device in which the claimed design is embodied and form no part of the claimed design.
